UNITED STATES PATENT OFFICE

2,002,978

APPARATUS FOR CONCENTRATING ORES

Edward Wilson Davis, Minneapolis, Minn.

Application April 11, 1931, Serial No. 529,412

15 Claims. (Cl. 209—232)

My invention relates to an improved apparatus for the concentration of iron ore in which magnetic force or attraction is utilized to cause the adhering together and precipitation of particles of iron mineral, such as magnetite, which may be mingled with particles of sand or gravel of substantially equal weight and which in a gravity separator would be carried out with the tailings of the machine.

10 This application is a continuation in part of my application Serial No. 431,092, filed February 25, 1930, and the invention is an improvement on the apparatus described in my United States Patent No. 1,153,037 issued September 5, 1915.

15 The present invention provides means for more accurate control of the concentrating operation with resultant cleaner separation of the magnetic mineral particles from the gangue particles and with production of a concentrate containing 20 a relatively small amount of water as compared with the product of earlier practice. My invention further makes it possible to treat relatively coarsely comminuted ores and effects an increase 25 in the capacity of the apparatus as compared with apparatus of similar size heretofore used.

In the earlier apparatus, as described in my Patent No. 1,153,037, it was found that only finely comminuted ores could be satisfactorily concentrated. With relatively coarsely comminuted ores, the coarser gangue particles could not be overflowed at the tailings weir except by increasing the rate of agitation to a point where considerable loss of magnetic mineral particles in the overflow would result. After considerable 30 experimental work and study, it has been discovered that by maintaining a condition of relatively low agitation near the tailings overflow weir and increasing the density of the pulp the coarser gangue particles can be flowed over without loss of magnetic mineral particles. At the same time, it is necessary to maintain a higher degree of agitation in the upper portions of the inclined troughs in which the pulp is treated in order to produce sufficient agitation for cleaning 35 the concentrate. I have found that these two functions can be performed simultaneously in the same apparatus by providing spiral agitating and conveying scrapers having a very small pitch at the lower or tailings overflow end of the apparatus and a higher pitch at the upper end.

40 Further, by thus varying the pitch of the spirals to a suitable extent, it is possible to rotate the spirals at a higher speed than in apparatus hitherto used and thereby increase the capacity without increasing loss of the magnetic mineral. By 45

operating with a denser pulp, economy in the use of water is also effected.

It has further been discovered that for the best results, namely, large capacity, high grade concentrate and low tailing losses, it is advantageous to regulate the clearance between the spirals and the strong magnetic pole pieces of the apparatus. It has been found that when the clearance is small, the grade of the concentrate is lower, whereas when the clearance is greater 10 and within certain limits depending upon the fineness and character of the ore, the grade of the concentrate is raised to a marked degree, without undue decrease in capacity and without increase in tailing losses. This improvement may 15 be explained as due to the fact that with the greater clearance, greater washing action is permitted and the spirals function not only as conveyors for moving the concentrate upwardly of the troughs toward the concentrate discharge, 20 but also to a greater extent as agitators to stir and break up the bodies of the magnetic material adhering to the magnets, thereby liberating gangue particles that may have become attached to and locked within the magnetic material. A further feature of the invention, therefore, consists of means for adjusting the relation of the spirals to the strong pole pieces so as to regulate the grade of the concentrate as desired and also to compensate for wear of the spirals. 25

Another feature of the present invention consists in so arranging the pole pieces and correlating the rotation of the agitating and conveying scrapers thereto that the iron mineral as it is collected and conveyed up the inclined 30 troughs toward the concentrate discharge and the non-magnetic gangue mineral flowing down toward the tailings overflow tend to follow separate paths and thereby keep from becoming 35 remixed.

Still another feature of the invention resides in the provision of an elevated discharge for the concentrate whereby the carrying forward with the concentrate of excessive amounts of water, as for instance when the scrapers are operated 45 at higher speeds, is prevented and the concentrate is dewatered to a very considerable extent.

The principle of operation and novel features of the invention will be more fully understood from the following description, taken in conjunction with the accompanying drawings, in which similar reference characters refer to similar parts throughout the several views.

Figure 1 is a plan of one form of apparatus embodying my invention.

Figure 2 is a longitudinal sectional elevation. Figure 3 is a detail view of the agitating and conveying means included in the apparatus shown in Figures 1 and 2.

5 Figure 4 is a transverse sectional elevation taken on line 4-4 of Figure 2.

Figure 5 is a transverse sectional elevation taken on line 5-5 of Figure 2.

10 Figure 6 is a detail view in plan of the spiral driving means showing bearing adjustments.

Figure 7 is a sectional view taken on line 7-7 of Figure 6.

Figure 8 is a sectional view taken on line 8-8 of Figure 7.

15 Figure 9 is a detail view in end elevation of the spiral driving means showing bearing adjustments.

Figure 10 is a diagram showing the movement of spiral for adjustment as wear decreases its 20 diameter.

25 In the drawings, 10 represents a concentrator of the log washer type including two inclined troughs 12, semi-circular in cross-section and formed by the energized pole piece 14, the non-magnetic bottom plates 16, the filler pieces 18 and the side walls 20. Mounted to rotate in the troughs 12 are shafts 22 and 24 carrying continuous spiral agitating and conveying scrapers 26 made of a non-magnetic material such as copper, brass or the like. The shafts 22 and 24 are 30 driven through suitable gears 27 by any convenient power means not shown. The pole piece 14 is magnetized by the magnets 28 having suitable windings 30. The filler pieces 18 are likewise energized but it is important that the windings or other arrangements provided for this purpose are such that the magnetic fields established by such pieces shall be weaker than the field established by the pole piece 14, for the 35 reasons hereinafter more fully discussed. In the drawings, the filler pieces 18 are arranged in circuit with the magnets 28 through the base member 29 and the side members 19. I have shown two troughs in the drawings, but any number 40 may be used. The overflow weir 32 and a launder 34 are provided at the lower end of the concentrator for discharge of the tailings, and at the upper end is a chute 38 having an inlet opening 36 elevated above the bottom of the troughs to 45 prevent water introduced for washing the concentrate in the upper portion of the troughs from flowing out with the concentrate instead of passing downwardly through the lower ends of the troughs. In the drawings, the pole piece 14 is 50 shown as terminating just short of the opening 36 and a raised lip 40 of suitable sheet metal is 55 provided for effecting the elevated discharge.

The ore to be treated is fed by any suitable means into the feed box 42 at a point near the lower end of the apparatus from which it passes 60 into the troughs 12 through the opening 44. Water pipes, not shown, are provided near the feed inlet to keep the pulp at the desired density.

65 Spray pipes 46 are so placed as to wash the gangue from the material on the curved filler pieces 18 and the pole piece 14 onto the bottom plates 16 of the troughs 12. The sprays also serve to remove material adhering to and carried over in the rotation of the spiral scrapers 26.

70 The spiral scrapers 26 have a varying pitch, the greatest pitch being at the upper end and the smallest pitch at the lower end. In order to aid in conveying the partially dewatered concentrate upwardly toward the discharge opening 36 75 and to produce increased agitation, additional

spiral scrapers may be provided in the upper ends of the troughs. In the drawings, a scraper 26a is shown as mounted in equi-spaced relation to the scraper 26 on each of the shafts 22 and 24 and extending from a point near, but some distance from, the lower end of each shaft to the upper end. Additional scrapers 26b and 26c, mounted in equi-spaced relation to the scrapers 26 and 26a, are shown as extending from a point about one-third of the distance from the lower end of each shaft to the upper end. Rods 29 may be spaced about the shafts 22 and 24 and joined to the scrapers to maintain them in equi-spaced relation.

10 While the pitch and number of spiral scrapers 15 used may be varied somewhat to meet different conditions and to treat different kinds of materials, my investigations have shown that advantageous results may be obtained in treating magnetite ores such as those occurring in the Mesabi 20 district of Minnesota if in a concentrator having an inside length of 18 feet the scraper 26 is mounted on the shaft 22 or the shaft 24 with a pitch of 2 inches between turns for the first 2 feet from the lower end, with a pitch of 4 inches 25 for the second 2-foot section, with a pitch of 8 inches for the third 2-foot section and with a pitch of 16 inches in the upper 12-foot section. In this example, the second scraper 26a begins 30 at a point 4 feet from the lower end and continues to the upper end with the same variation in pitch as the scraper 26. The scrapers 26b and 26c begin at a point 6 feet from the lower end and continue to the upper end with a pitch 35 of 16 inches between turns in equi-spaced relation to the scrapers 26 and 26a.

40 Figures 6, 7, 8 and 9 show in detail one form of means for adjustment of the relation of the spirals to the pole piece 14. At the upper end of the apparatus a bracket 48 carries the driving mechanism for the spirals. This bracket 48 is slidably supported on the bracket 52, which is attached rigidly to the side walls 20. Threaded members 50 engage the bracket 48 and turn 45 freely in the bracket 52.

45 By manipulation of the threaded members 50, the bracket 48, carrying the bearings 54 for the spirals, may be raised or lowered vertically with respect to the pole piece 14. The bearings 54 are movable in a horizontal direction and may be 50 moved toward or away from the pole piece 14 by means of the turnbuckle 56. The pinions 58 are slidably mounted on the shaft 60 so that they 55 may be moved to conform with the horizontal movement of the bearings.

55 The bearings at the lower end of the apparatus may be adjusted in the same manner as described above for the adjustment of the bearings at the upper end of the apparatus.

60 The diagram, Figure 10, shows the preferred adjustment of the spiral. In this diagram, 62 is the original circumference, 64 is the circumference after wear and 66 is the circumference of the spiral when adjusted to its new position. 68 is the original center and 72 is the new center 65 when the axis of the spiral has been moved along the line 70-70 toward the strong pole piece 14. If the radius has been reduced by wear one-quarter of an inch, for example, the center should be moved one-quarter of an inch toward the 70 pole piece 14 along the line 70-70. Adjustment of the spiral toward the pole piece 14 along the line 70-70 has been found to insure good results in practice. However, it will be understood that it is not essential that the spiral be adjusted pre- 75

cisely along the line 70—70. The important thing is to adjust it toward or away from the strong pole piece 14 so as to give the best results with the particular material being treated.

5 The operation of the apparatus is as follows:— The comminuted iron ore in the form of a pulp is fed to the apparatus through the distributing feed box 42. The shafts 22 and 24 carrying the spiral scrapers 26, 26a, 26b and 26c are rotated in opposite directions toward the magnetic pole piece 14, as shown by the arrows (see Figures 4 and 5). The material in the troughs 12 is thus not only propelled up the inclined troughs, but also toward the pole piece 14. The 10 particles of iron mineral thus entering the magnetic field are not only drawn toward the pole piece 14, but adhere together, forming agglomerates which with increase of size show a greater 15 tendency to sink in the pulp than the unagglomerated gangue particles.

As the magnetized particles of iron mineral are propelled up the inclined troughs they tend to take a position at or near the pole piece 14, while the heavier gangue particles which may also tend 20 to some extent to be propelled up the incline, take a position on the non-magnetic bottom plates 16 of the troughs 12. The gangue particles here meet the water from the spray pipes 46 and are washed down the channels formed by the non-magnetic bottom plates 16 at the bottom of the 25 troughs 12, back into the main body of the pulp, where they eventually overflow together with the lighter gangue particles over the weir 32. The flow of the gangue particles down the 30 troughs is also facilitated due to the adjustment of the spirals toward the strong pole piece to compensate for wear and preserve the optimum clearance, which adjustment results in a greater 35 clearance on the sides of the troughs remote from the strong pole piece 14. The iron mineral collects on the curved surface of the pole piece 14, and is propelled along the same and finally 40 discharged over the lip 40 through the openings 36.

Owing to the fact that the scrapers are rotated in such a direction as to tend to carry the magnetic particles of iron mineral up onto the strong pole piece 14, the particles collected thereon in moving forward toward the concentrate discharge are carried up out of the liquid pulp, thereby permitting a large portion of the 45 contained water and gangue particles carried thereby to drain away and flow back down the troughs 12 toward the tailings discharge. This is a marked improvement over my earlier patent above mentioned which contemplated an operation in which the scrapers were so rotated that the particles of iron mineral tended to become remixed with the gangue particles, thus counteracting the separating effect of the magnets. By arranging the pole pieces in the manner shown and rotating the spirals so as to carry the iron mineral up 50 out of the bottom of the trough 12, the magnetic mineral being conveyed up the inclined trough and the non-magnetic gangue material flowing down the inclined trough tend to follow separate paths.

The dewatering and washing of the concentrate is facilitated by providing the elevated discharge lip 40. This lip is made sufficiently high to prevent water introduced through the spray pipes 46 from flowing out the concentrate discharge opening 36 and carrying therewith any gangue washed away from the concentrate.

As compared with the earlier practice in which 55 concentrate recovered ordinarily contained about

90% water, a concentrate may be obtained by operating according to the present invention that will contain about 50% water.

In order closely to control the grade of the concentrate, the spirals are adjusted toward or away from the strong pole piece so as to afford optimum results with the particular material undergoing treatment. The clearance that it is desirable to maintain will vary with the type of material treated over a range of about one-eighth 10 of an inch up to about one inch. If the ore is an easy one to concentrate and contains little middling, the clearance may be smaller; however, if the ore is very fine, containing considerable middling, and is difficult to separate, the clearance should be larger. With one type of comparatively coarse ore, i. e.—65 mesh, very satisfactory results were obtained when operating with a clearance of about three-quarters of an 15 inch. Once the optimum clearance has been determined for a particular ore, no further adjustment is needed except from time to time to compensate for wear of the spirals. However, this feature of being able to adjust the spirals to compensate for wear is an important one. Hereto- 20 fore when the spirals had worn so that a clearance of more than about one inch was produced, it was necessary to replace them with new ones. By means of the adjustable bearings the life of the spiral is greatly prolonged.

As above stated, the filler pieces 18 are energized. However, it is desirable that the fields so established shall be weaker than that of the pole piece 14, in order that the collection of the magnetic ore concentrate on this pole piece shall be 25 facilitated. While the filler pieces 18 function as weaker magnetic fields, they may serve to hasten the settling out of the magnetic mineral particles, which are then transferred to the stronger pole 30 14, due to rotation of the scrapers.

While I have shown the pole piece 14 and the 35 filler pieces 18 as directly in contact with the pulp, it will be understood that the troughs 12 may be formed separately of a suitable non-magnetic material, with the pole piece 14 and the 40 pieces 18 when they are likewise energized, shaped to conform to the bottom of the trough, as shown for example in my earlier patent above mentioned.

It will be understood that various other 45 changes may be made in the details of construction and operation without departing from the invention which is not to be deemed as limited other than as indicated by the appended claims.

I claim:

1. In an ore concentrator, means defining an inclined elongated agitating zone having a liquid and tailings overflow at the lower end and a concentrate discharge at the upper end, magnetic means disposed adjacent said zone to establish 50 therein a magnetic field varying in intensity from one side of said zone to the other, means for so agitating a liquid pulp fed to said agitating zone as to move the magnetizable values contained therein toward the stronger portion of said magnetic field and for conveying them upwardly through said zone to a concentrate discharge, said magnetic means being so disposed with respect to said agitating zone as to cause the magnetizable values to assume a path in their travel 55 upwardly toward the concentrate discharge substantially completely separate from that of the non-magnetic materials contained in the portions of the liquid pulp that flow downwardly through said agitating zone toward the liquid and tail- 60 65 70 75

- ings overflow and said agitating means being adapted to agitate said pulp less violently in the lower end of said zone than in the upper end thereof.
2. An ore concentrator comprising an inclined trough having a liquid and tailings overflow at the lower end and a concentrate discharge at the upper end, magnetic pole pieces disposed adjacent said trough for establishing a magnetic field effective in the space embraced in said trough and varying in intensity from one side of said trough to the other, means for agitating and conveying upwardly through said trough a concentrate consisting of magnetizable values collected from a pulp fed thereto, said concentrate discharge being located in spaced relation to and above the bottom of said trough, said trough having a portion adjacent the concentrate discharge extending a substantial distance above the normal water level in the lower end of said trough as defined by the height of the liquid and tailings overflow, thereby permitting liquids added to and entrained with the concentrate brought into such upper portion to drain away therefrom before such concentrate is discharged from the machine, said agitating means being adapted to move the magnetizable values in said pulp toward the side of said trough situated in the stronger portion of said magnetic field, and to agitate said pulp less violently in the lower end of said zone than in the upper end thereof, and means for adjusting said agitating and conveying means toward and away from the bottom of said trough to regulate the degree of agitation of the pulp treated in said trough.
3. An ore concentrator comprising an inclined trough curved in cross-section, magnetic pole pieces extending continuously beneath and along both sides of said trough and conforming to the curvature thereof, means for strongly energizing one of said pole pieces and relatively weakly energizing the other pole piece, and a rotating scraper for feeding a material upwardly in said trough, said scraper being adapted to be so driven as to tend in rotation to carry magnetizable values in said material up onto the side of the trough within the magnetic field of said strong pole piece, and being so formed as to maintain a condition of relatively low agitation in the pulp disposed in the lower end of the trough as compared with the agitation produced thereby in the upper end thereof.
4. An ore concentrator comprising an inclined trough, curved in cross-section, and having a liquid overflow at the lower end and a concentrate discharge at the upper end, a magnetic pole piece extending continuously beneath and along one side of said trough and conforming to the curvature thereof, a second magnetic pole piece disposed adjacent the opposite side of said trough, means for strongly energizing said first-mentioned pole piece and relatively weakly energizing the other pole piece, an agitating and separating conveyor rotatably mounted in said trough and having one end submerged, said conveyor comprising a shaft carrying a continuous spiral scraper varying from a low pitch on the submerged end to a relatively high pitch at the concentrate discharge end of the trough, and means for rotating said conveyor in such direction as to cause it to tend to carry magnetizable values up onto the side of the trough within the magnetic field of said first-mentioned pole piece.
5. An ore concentrator comprising an inclined trough, curved in cross-section, and having a liquid overflow at the lower end and a concentrate discharge at the upper end, a magnetic pole piece conforming to the curvature of the trough and extending beneath and along one side thereof, a second magnetic pole piece disposed adjacent the opposite side of said trough, means for strongly energizing said first-mentioned pole piece and relatively weakly energizing the other pole piece, an agitating and separating conveyor rotatably mounted in said trough and comprising means for producing a relatively small amount of agitation in the lower end of said trough and a relatively great amount of agitation in the upper part thereof, said conveyor being so driven as to tend to carry magnetizable values up onto the side of the trough within the magnetic field of said first-mentioned pole piece, means for introducing water into said trough adjacent the concentrate discharge, and means preventing free flow of the water so introduced through the concentrate discharge.
6. An ore concentrator comprising a pair of adjacently arranged inclined troughs, each substantially semi-circular in cross-section, and having a liquid overflow at the lower end and a concentrate discharge at the upper end, a magnetic pole piece extending between and beneath said troughs and conforming to the curvature thereof, other pole pieces disposed adjacent the sides of said troughs remote from said first-mentioned pole piece, means for strongly energizing said first-mentioned pole piece and relatively weakly energizing the other pole pieces, rotating scrapers mounted in said troughs for agitating pulp contained therein and conveying solids upwardly in said troughs, and means for so rotating said scrapers as to cause said scrapers to carry magnetic particles collecting upon said first-mentioned pole piece upward upon the same out of the bottom of the troughs and forward toward the concentrate discharge, said scrapers being so formed as to maintain a condition of relatively low agitation in the pulp disposed in the lower ends of the troughs as compared with the agitation produced thereby in the upper ends thereof.
7. In an ore concentrator comprising an inclined trough, curved in cross-section and having a liquid overflow at the lower end and a concentrate discharge at the upper end, an agitating and separating conveyor rotatably mounted in said trough and having one end submerged, said conveyor comprising a shaft carrying a continuous spiral scraper varying from a low pitch at the submerged end to a relatively high pitch at the concentrate discharge end of the trough, and means for rotating said conveyor.
8. In an ore concentrator comprising an inclined trough, curved in cross-section and having a liquid overflow at the lower end and a concentrate discharge at the upper end, an agitating and separating conveyor rotatably mounted in said trough and having one end submerged, said conveyor comprising a shaft carrying a continuous spiral scraper varying from a low pitch at the submerged end to a relatively high pitch at the concentrate discharge end of the trough, said shaft also carrying a second spiral scraper beginning at a point near to, but removed from the lower end of the shaft and extending continuously with and in equi-spaced relation to the first-mentioned spiral to the concentrate discharge end of the trough.
9. In an ore concentrator comprising an inclined trough, curved in cross-section, and having a liquid overflow at the lower end and a concentrate discharge at the upper end, an agitating and separating conveyor rotatably mounted in said trough and comprising means for producing a relatively small amount of agitation in the lower end of said trough and a relatively great amount of agitation in the upper part thereof, said conveyor being so driven as to tend to carry magnetizable values up onto the side of the trough within the magnetic field of said first-mentioned pole piece, means for introducing water into said trough adjacent the concentrate discharge, and means preventing free flow of the water so introduced through the concentrate discharge.

- trate discharge at the upper end, an agitating and separating conveyor rotatably mounted in said trough and having one end submerged, said conveyor comprising a single shaft carrying a continuous spiral scraper, consisting of a portion of low pitch adjacent the lower end, a portion of relatively high pitch adjacent the concentrate discharge ends, and a portion of intermediate pitch between said portions, and a second spiral scraper 5 extending continuously with and in equi-spaced relation to the first-mentioned spiral from a point adjacent the lower end of the intermediate pitched portion of said first-mentioned spiral to a point adjacent the concentrate discharge end.
10. In an ore concentrator comprising an inclined trough, curved in cross-section, and having a liquid overflow at the lower end and a concentrate discharge at the upper end, an agitating and separating conveyor rotatably mounted in said trough and having one end submerged, said conveyor comprising a single shaft carrying a continuous spiral scraper, consisting of a portion of low pitch adjacent the lower end, a portion of relatively high pitch adjacent the concentrate discharge end, and a portion of intermediate pitch between said portions, a second spiral scraper 15 extending continuously with and in equi-spaced relation to the first-mentioned spiral from a point adjacent the lower end of the intermediate pitched portion of said first-mentioned spiral to a point adjacent the concentrate discharge end.
20. In an ore concentrator comprising an inclined trough, curved in cross-section, and having a liquid overflow at the lower end and a concentrate discharge at the upper end, an agitating and separating conveyor rotatably mounted in said trough and having one end submerged, said conveyor comprising a single shaft carrying a continuous spiral scraper, consisting of a portion of low pitch adjacent the lower end, a portion of relatively high pitch adjacent the concentrate discharge end, and a portion of intermediate pitch between said portions, a second spiral scraper 25 extending continuously with and in equi-spaced relation to the first-mentioned spiral from a point adjacent the lower end of the intermediate pitched portion of said first-mentioned spiral to a point adjacent the concentrate discharge end.
25. In an ore concentrator comprising an inclined trough, curved in cross-section, and having a liquid overflow at the lower end and a concentrate discharge at the upper end, a magnetic pole piece extending beneath and along one side of said trough, a second magnetic pole piece disposed adjacent the opposite side of said trough, means for strongly energizing said first-mentioned pole piece and relatively weakly energizing the other pole piece, an agitating and separating conveyor rotatably mounted in said trough and having one end submerged, said conveyor comprising a shaft 30 carrying a continuous spiral scraper varying from a low pitch at the submerged end to a relatively high pitch at the concentrate discharge end of the trough, means for rotating said conveyor in such direction as to cause it to tend to carry the concentrate up onto the side of the trough within the magnetic field of said first-mentioned pole piece, and means for preventing flow of pulp from the bottom of said trough through the concentrate discharge.
30. An ore concentrator comprising an inclined trough, curved in cross-section, magnetic pole pieces so associated with said trough as to establish a strong magnetic field along one side thereof, and a weaker magnetic field along the other side thereof, an agitating and separating conveyor rotatably mounted in said trough and having one end submerged and the other end above the normal pulp level, means for rotating said conveyor in such direction as to cause it to tend to carry the concentrate up onto the side of the trough within the strong magnetic field, said conveyor being so formed as to agitate the contents of said trough less violently in the lower portions than in the upper portions thereof, means for introducing water into the trough adjacent the upper end thereof, and an elevated discharge at the upper end of the trough permitting discharge of the concentrate as it is fed along the side of the trough while preventing flow of liquid pulp through said discharge from the bottom of the trough.
35. An ore concentrator comprising an inclined trough, magnetic poles of unequal strength extending along the bottom and sides of said trough, a spiral scraper rotatably mounted in said trough for agitating pulp contained therein and conveying solids upwardly in said trough, and means for adjusting said scraper toward and away from the stronger of said magnetic poles.
40. An ore concentrator comprising an inclined trough, curved in cross-section, magnetic pole pieces extending continuously beneath and along both sides of said trough and conforming to the curvature thereof, means for strongly energizing one of said pole pieces and relatively weakly energizing the other pole piece, a rotating scraper for feeding a solid material upwardly in said trough, said scraper being so driven as to carry the material up onto the side of the trough within the magnetic field of said strong pole piece, and means for adjusting said scraper toward and away from said strong pole piece.
45. In an ore concentrator comprising an inclined trough having a liquid overflow at the lower end and a concentrate discharge at the upper end, an agitating and separating conveyor rotatably mounted in said trough, magnetic means disposed adjacent said trough for establishing a magnetic field effective in the space embraced in said trough and varying in intensity from one side of said trough to the other, and means for adjusting said conveyor bodily toward and away from the bottom of said trough and toward and away from the side of said trough that is disposed in the stronger portion of said field, for regulating the degree of agitation of the solids carried by a liquid fed through said trough.

EDWARD WILSON DAVIS.
